UNITED STATES PATENT OFFICE.

WILLIAM E. TINNEY, OF NEW YORK, N. Y.

TELEGRAPHIC KEY OR TRANSMITTER.

SPECIFICATION forming part of Letters Patent No. 239,270, dated March 22, 1881.

Application filed October 1, 1880. (Model.)

To all whom it may concern:

Be it known that I, WILLIAM ESSEX TINNEY, of New York city, in the county and State of New York, have invented certain new and useful Improvements in Telegraphic Keys or Transmitters, of which the following is a specification.

The object of my invention is to save labor in sending telegraphic matter, secure greater rapidity in sending, also to make a key or transmitter which can be used by other than skilled operators. This I accomplish by constructing the telegraphic letters, figures, and other characters of metal points separated by insulated material, the said metal points or blocks which represent the dots (—) being, say, one-sixteenth of an inch in thickness, and those which represent the dashes, (—), say, three-sixteenths thick. The spaces, (—), which are of glass or other insulating material, are of about the same thickness as the dots. These are arranged in combination with each other in the order of the dots, spaces, and dashes required to form the various letters, figures, and other characters in use, each letter or character being separate and apart from the others, but all connected to one wire.

The invention consists in keys proper, which are placed in proper relation to the above-described keys, and are armed with the usual metal points. Said keys are connected with the other wire, and capable of lateral and longitudinal motions, so that when pressed upon the metal point will advance to and press upon the face of the letter above the first metal block, and as the pressure is continued it is moved longitudinally over the face of the letter, and thus successively comes in contact with the metal points and insulated material representing the dots, spaces, and dashes, (—), as may be required to form any telegraphic character. When the pressure is removed the metal point of the key proper leaves the face of the letter, and the key moves back to its original position, thereby preventing an inverse repetition of the letter.

The invention is shown in detail in the drawings forming a part of this specification, in which all similar letters of reference indicate like parts in all the figures.

Figure 1 is a front view of two of the let-

ters, A (—) B, (— — —) and their respective keys. Fig. 2 is an end view of the same. Fig. 3 is a vertical section of one of the letters, showing the metal blocks and insulating material arranged in proper order to give the letter H, (— — —).

A is the key proper, constructed in two parts—i. e., of an arm hinged to the top of a movable shaft. B is said shaft. It moves longitudinally in its case B', being guided by the small arms d, which project from its sides just below its top or head, and slide in slots h of the case B', also by the lower end passing through a hole in the bottom of said case.

E is a spiral spring, which is coiled around shaft B, its lower end bearing on the bottom of the case and its top bearing against the under side of the guide-arms d.

The arm C may be described as consisting of a body, which at one end hinges to the top of the shaft B, a being the pivot of the hinge. This body projects outwardly at a right angle to shaft B, and from it projects upward a short shaft, which is armed with the finger-knob D. The body then curves down and forms the arm proper, which is about one-half the length of shaft B, with which it is parallel, and about five-eighths of an inch from it. At the lower end this arm curves to one side about one-fourth of an inch, and near its termination is armed with the usual metal point b.

c is a spring, which takes bearing on the lower end of the arm and holds it out from the shaft B.

H is a metallic case, open at front and back, and provided with a set-screw, i, at its top. In this case are placed the metal blocks and insulating material required to form the desired letter. Thus, for the letter A there is first placed a piece of glass one-eighth inch thick, then metal three-sixteenths of an inch thick, then glass one-sixteenth of an inch thick, then one-sixteenth of an inch of metal, and the remaining space filled with insulating material. The set-screw i being screwed down binds all together. The face of the letter is then ground off even and smooth, as shown in Fig. 3. e e are the insulating-blocks, (spaces,) and f f are the metal blocks, (dots and dashes.) It will be understood that said metal blocks should be in connection with the sides of the

case H, which in turn is connected to one of the line-wires, while the key C is in connection with the other. A series of these keys and letters are then arranged on a common base 5 in such number as to give one key for each letter or character required in telegraphy, the key-board of the complete apparatus being similar in appearance to the Remington type-writer.

- 10 Operation: On pressing on the knob of the letter A the point b on the lower end of the arm C advances to and presses on the insulating material just below the top of case H, then descends, sliding over the face of the letter.
- 15 The shaft B moving down compresses the spiral spring E. When the point b has arrived at the end of the letter the pressure is removed, and the spring c throws the said point away

from the letter, and the spiral spring E raises the key A to its original position.

Having thus described my invention, what I claim, and desire Letters Patent for, is—

A telegraph key or transmitter consisting of a vertical shaft adapted to move up and down in a retaining-case, and having a hinged 25 projecting arm attached thereto, which makes electrical contact on its downward movement with a series of metal blocks, substantially as described, but is borne away from said metal blocks by a spring on its upward movement, 30 in the manner and for the purpose set forth.

WILLIAM ESSEX TINNEY.
